CLAIM

The ornamental design for a folding towel rack, as shown and described.

DESCRIPTION

FIG. 1 is a front perspective view of a folding towel rack in an unfolded configuration showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left-side elevational view thereof.

FIG. 7 is a right-side elevational view thereof.

FIG. 8 is a front perspective view of a folding towel rack in a folded configuration.

FIG. 9 is a front elevational view of the folding towel rack shown in FIG. 8.

FIG. 10 is a rear elevational view of the folding towel rack shown in FIG. 8.

FIG. 11 is a top plan view of the folding towel rack shown in FIG. 8.

FIG. 12 is a bottom plan view of the folding towel rack shown in FIG. 8.

FIG. 13 is a left-side elevational view of the folding towel rack shown in FIG. 8; and,

FIG. 14 is a right-side elevational view of the folding towel rack shown in FIG. 8.

The broken lines form no part of the claimed design.
